(57) **CLAIM**

The ornamental design for a bread storage container as shown and described.

DESCRIPTION

1. Bread storage container

1.1 : Perspective

1.2 : Perspective

1.3 : Top

1.4 : Left

1.5 : Front

1.6 : Right

1.7 : Back

1.8 : Bottom

1.9 : Perspective

1.10 : Perspective

The design lies in the shape and configuration of the articles depicted; views 1.9 and 1.10 show drawers in an open state, whereas the remaining views show the drawers in a closed state. All broken lines of the bread storage container represent unclaimed features of the article.

1 Claim, 10 Drawing Sheets
